(57) **CLAIM**

The ornamental design for an exercise device, as shown and described.

DESCRIPTION

FIG. 1 is a perspective view of a second embodiment thereof in the lowered position;

FIG. 2 is a front elevational view of FIG. 1;

FIG. 3 is a rear elevational view of FIG. 1;

FIG. 4 is a right-side elevational view of FIG. 1, the left-side elevational view being a mirror image thereof;

FIG. 5 is a top plan view of FIG. 1;

FIG. 6 is a rear elevational view of FIG. 1;

FIG. 7 is a right-side elevational view of the second embodiment in the raised position, the left-side elevational view being a mirror image; and,

FIG. 8 is a front elevational view of FIG. 7, the rear elevational view being a mirror image thereof.

The broken lines in the figures depict portions of the exercise device that form no part of the claimed design.

1 Claim, 7 Drawing Sheets
